Clifford C. Voss, Clawson, Mich., and Allen R. Williams, Jr., Peabody, Mass., assignors to Chrysler Corporation, Highland Park, Mich., a corporation of Delaware

Filed May 2, 1960, Ser. No. 60,415

Term of patent 7 years

(Cl. D48—32)

Fig. 1 is a side elevational view of an automobile tail lamp unit showing our new design;

Fig. 2 is a front elevational view thereof;

Fig. 3 is a side elevational view of the side opposite to that illustrated in Fig. 1; and

Figs. 4, 5 and 6 are sectional views taken on the lines 4—4, 5—5 and 6—6, respectively, of Fig. 1.

The dominant features of our design reside in the full line portions of the drawing.

We claim:

The ornamental design for an automobile tail lamp unit, substantially as shown and described.
